UNITED STATES PATENT OFFICE.

WILLIAM A. REAPER, OF MONROE, MICHIGAN.

DESIGN FOR ORNAMENTATION FOR A GOBLET, BOWL, OR SIMILAR ARTICLE.

61,103.

Specification for Design.

Patented June 20, 1922.

Application filed August 26, 1921. Serial No. 495,831. Term of patent 7 years.

To all whom it may concern:

Be it known that I, WILLIAM A. REAPER, a citizen of the United States, residing at Monroe, in the county of Monroe and State of Michigan, have invented a new, original, and ornamental Design for Ornamentation for a Goblet, Bowl, or Similar Article, of which the following is a specification, reference being had to the accompanying drawing, forming part thereof.

The figure is a view of a vessel to which the design is applied.

I claim:

The ornamental design for ornamentation for a goblet, bowl, or similar article, as shown.

WILLIAM A. REAPER.
